SHIPPING AND DISPLAY PACKAGE

Robert C. Bush, Coopers Plains, N.Y., assignor to Corning Glass Works, Corning, N.Y., a corporation of New York

Filed Dec. 27, 1957, Ser. No. 705,632

1 Claim. (Cl. 206—65)

The present invention relates to packages such as containers or cartons of paper board or the like, usually provided with compartmented assemblies, for holding a plurality of articles therein separated from one another to protect them against breakage in handling and shipment. Such a package is ordinarily opened by removal of its top wall, and thus merely exposing a top plan view of the articles arrayed in its compartmented assembly, which alone or in conjunction with other layers of compartmented assemblies, extend the full carton height to adequately protect the articles contained therein during handling and shipment.

The present invention, in its simplest concept, comprises a package of the foregoing general character which employs a carton marked for separation along a line substantially level with the top of the lowermost of two vertically stacked like compartmented assemblies. In such package the height of the lowermost of the compartmented assemblies is such that with the carton separated along the marked line and the upper portion removed along with the upper of the compartmented assemblies the articles will be retained in substantially their packed positions within the lower compartmented assembly and the remaining portion of the carton, while being substantially wholly displayed in an attractive manner.

For a more comprehensive understanding of the invention reference may be had to the accompanying sheet of drawing wherein:

Fig. 1 is a top plan view of a package embodying the invention comprising a paperboard carton having its top side partly broken away to expose a compartmented assembly therein having its respective cells or compartments occupied by articles of ware.

Fig. 2 is side elevation of the package of Fig. 1 with part of a sidewall broken away.

Fig. 3 is a perspective view of the upper of two similarly celled or compartmented assemblies embodied in the package.

Fig. 3a is a perspective view of the lower of the two compartmented assemblies of the package.

Fig. 4 is an exploded view of a fragment of the package when separated along the separating line indicated in Fig. 2.

Fig. 5 is an end elevation of a fragment of the lower portion of the package with the articles retained therein for display by the lower of the compartmented assemblies.

2

Referring to the drawing in detail, the package comprises a conventional closed carton 11 having vertically stacked therein like compartmented assemblies 21 and 31 respectively and containing a number of shallow dishes 41 in their respective compartments, such as 22 and 32, which are in vertical register.

The top level of assembly 31 is indicated on the exterior of the carton 11 by an interrupted line 12 extending thereabout suitably labeled for suggesting severance along such line, thus, dividing the carton wall into upper and lower portions 13 and 14, respectively.

When the package contents are to be displayed, the carton wall is simply severed along line 12 and its upper portion 13 lifted from about assembly 21. The assembly 21 is then also lifted from about the dishes 41 to leave them neatly held in position for display jointly by the surrounding carton wall portion 14 and the compartmented assembly 31.

As will be understood, it is within the concept of the invention to provide packages containing successive layers of articles vertically separated from one another by plain sheets of paperboard. Such cartons may be provided with a number of lines indicating successively lower levels at which upper portions of the carton and assemblies surrounded by them may be removed to successively expose for display, successively lower layers of articles in such a package as the articles therein are sold. Other variations of the invention coming within the definitions set forth in the appended claims will occur to those skilled in the art.

What is claimed is:

As an article of manufacture, a carton composed of paperboard or the like closed on all sides; two multi-compartmented assemblies identical as viewed from above, for retaining articles in such carton in a substantially upright position, stacked in vertical register with one another and the lower one of which is of small height compared to the height of the upper of said assemblies; said carton being exteriorly marked with a line thereabout along the line of juncture of said assemblies at which the carton may be severed and the upper portion thereof and the upper of said assemblies respectively removed to substantially fully expose articles retained therein to view while such articles continue to be retained on edge for display by the lower assembly and the remaining portion of such carton.
